UNITED STATES PATENT OFFICE.

JOHN F. PALMER, OF MILWAUKEE, WISCONSIN.

ROLL-PAPER HOLDER.

1,127,918.

Specification of Letters Patent.

Patented Feb. 9, 1915.

Application filed August 14, 1914. Serial No. 356,732.

To all whom it may concern:

Be it known that I, JOHN F. PALMER, a citizen of the United States, and resident of Milwaukee, in the county of Milwaukee and State of Wisconsin, have invented certain new and useful Improvements in Roll-Paper Holders; and I do hereby declare that the following is a full, clear, and exact description thereof.

10 My invention consists in what is herein particularly set forth with reference to the accompanying drawings and pointed out in the claims of this specification, its object being to provide simple, economical and efficient means by which to prevent the unwinding of more than a predetermined length of paper toweling or toilet paper from a roll of the same upon a spindle having supports that may constitute 15 arms of a wall-bracket.

Figure 1 of the drawings represents a plan view partly in horizontal section of a wall-bracket, a spring-controlled rotary spindle detachably connected to arms of 25 the bracket, the spindle being limited as to rotary movement, and a paper-roll core having detachable rigid connection with said spindle the plane of the sectioning being indicated by line 1—1 Fig 4; Fig. 2, a 30 partly sectional elevation of the bracket indicated by line 2—2 in Fig. 1; Figs. 3 and 4 transverse sectional views respectively indicated by lines 3—3, and 4—4 in Fig. 1; Fig. 5, a front elevation partly in section illustrating details of the mechanism herein specified, and Fig. 6, a plan view of a fragment of the paper-roll core illustrating a clip of a spindle-connecting device therewith.

40 Referring by numerals to the drawings, 7 indicates the back and 8 the forwardly extending arms of a wall-bracket preferably provided with horizontal slots 9 in said back thereof for the engagement of 45 fastening-bolts 10. The outer ends of the bracket-arms are provided with eyes. One of the eyes is engaged by the outer end of an arbor 11 on which a spindle 12 is loose, and a slidable bolt 13 carried by the spindle 50 engages another of the eyes to turn therein. The spindle is a casting of cylindrical contour having open sides and braced at intervals between its heads by transverse partitions. The arbor 11 extends through one 55 end and an adjacent partition of said spindle, the other end and another partition of

said spindle being engaged by the bolt 13. Surrounding the arbor and fastened at one end thereto is a spiral spring 14, the other end of the spring being attached to said 60 spindle. Arranged on the bolt 13 is a spiral-spring 15, the outer end of which opposes a pin 16, extending through said bolt, its other end being opposed to the spindle partition through which said bolt extends. Ex- 65 tending longitudinally of the spindle and integral therewith at one end of the same are diametrically opposite ribs 17 that engage grooves fashioned in a sheet-metal split-ring 18 set in one end of the hollow 70 core 19 of a roll of paper toweling or toilet-paper, the roll being indicated by dotted lines in Figs. 1, 3 and 4. The ring is provided with a flange 18' parallel to the roll-core, and prongs of the flange are struck 75 into said core to thereby fasten the same to said ring.

Keyed or otherwise fast on the arbor 11, between a support for the same and the adjacent head of the spindle, is an arm 20 80 in the path of a stop 21 on an end of the spindle, and the arm is provided with a lug 22 engaging a groove 23 in said support, whereby said arbor is held against rotation.

When the mechanism herein specified is organized for paper toweling, a draw on said toweling against resistance of the spring 14 will result in approximately one revolution of the spindle and roll therewith, whereby the amount of paper designed for one towel is unwound. This length of toweling being torn off, there is an automatic reverse motion of the spindle and roll due to expansion of the spring 14. 95

In an organization of the mechanism for toilet-paper, less unwind of the paper than for towel is desirable and to that end another stop is provided on the end of the spindle having the stop 21, the second stop 100 being shown as 24 in Fig. 5.

A roll of paper having been exhausted its core is torn away to provide for access to the bolt 13, and this bolt being retracted the spindle may be readily removed from 105 the supports to permit withdrawal of said core therefrom and the substitution of another cored roll on said spindle.

I claim:

1. The combination of supports, a spring-controlled rotary spindle in connection with the supports and provided at one end with

external longitudinal ribs, means limiting rotation of the spindle, and a ring having grooves engaged by the spindle-ribs, the ring being one that is rigidly secured inside 5 of one end of a paper roll core.

2. The combination of supports, a spring-controlled rotary spindle in connection with the supports and provided at one end with external longitudinal ribs, means limiting 10 rotation of the spindle, and a flanged ring having grooves engaged by the spindle-ribs, the ring being one that is set in one end of a paper core roll to which it is fastened by bending of its flange thereon.

15 3. The combination of supports, a spring-

controlled rotary spindle in connection with the supports and provided at one end with external longitudinal ribs, means limiting rotation of the spindle, and a grooved device engaged by each of the spindle-ribs 20 and which is rigidly secured inside of one end of a paper roll core.

In testimony that I claim the foregoing I have hereunto set my hand at Milwaukee in the county of Milwaukee and State of 25 Wisconsin in the presence of two witnesses.

J. F. PALMER.
